UNITED STATES PATENT OFFICE.

WILLIAM J. TOMPKINS, OF MOUNT VERNON, NEW YORK.

HEEL LIFT FOR SHOES.

Application filed April 9, 1920. Serial No. 372,435.

To all whom it may concern:

Be it known that I, WILLIAM J. TOMPKINS, a citizen of the United States, and resident of the city of Mount Vernon, in the 5 county and State of New York, have invented certain new and useful Improvements in Heel Lifts for Shoes, of which the following is a description.

This invention relates to heel lifts for 10 shoes, and more particularly to resilient or cushion heel lifts, of rubber or other similar material.

As is well known in the art, such resilient heel lifts for affording a cushion or 15 elastic tread for shoes have been produced in several different forms. In the application of a lift having a perfectly flat or plane attaching face to the shoe heel it is necessary to use an adhesive in order to retain 20 the marginal edges of the lift in close contact with the heel surface. It has been proposed to construct the lift with a rand on its attaching face, extending along its breast edge, each of the side edges, and the 25 rear edge, so that when pressure is applied to the tread face of the lift and the lift then securely nailed to the shoe, the marginal edges of the lift will exert a resilient compressing action against the face of the shoe 30 heel and thus closely hug the leather surface without necessitating the use of an adhesive. However, this form of heel lift has been found objectionable since it is generally necessary to trim off the edges of the 35 lift after it has been secured to the shoe heel, and it was then found that the breast corners of the lift were not in positive contact with the heel face. This is due to the 40 fact that the meeting ends of the inclined surfaces of the rands along the breast and the side edges of the lift which extend at right angles to each other produce diagonally extending channels or depressions at 45 the breast corners of the lift. As a consequence when the lift is applied and secured to the shoe heel, after trimming the edges, gaps or spaces will be noticed at the 50 breast corners where the rand surfaces meet, such surfaces of the channels or depressions being out of contact with the leather shoe heel.

It is the primary object of the present invention to provide a resilient heel lift which is of such construction that a tight hugging 55 contact throughout the marginal edges of

the lift and at the breast corners thereof against the face of the shoe heel will be obtained without necessitating the use of an adhesive. In one embodiment of the invention the lift is formed with a perfectly 60 plain attaching face between its marginal edges, and the breast corners thereof are angularly offset with respect to the plane of the lift body, so that they project above the 65 attaching face of the lift. In another embodiment I propose to form the heel lift with a rand extending along only the side and rear edges of its attaching face, while the breast portion of the lift is longitudinally inclined in a plane at an obtuse angle 70 with relation to the plane of the body of the lift, so that the rand surfaces at the breast corners and the surface of said inclined breast portion will preferably merge together without presenting definite lines of 75 joinder, or without necessarily producing any noticeable channels or depressions at the breast corners, such as are characteristic of the type of heel lift to which I have above made reference.

It is another object of my invention to provide a heel lift having a flat or plane tread face and means on the attaching face of the lift to prevent the depression of said tread face when a compressing pressure is 80 applied in securing the lift to the shoe heel.

My present improvements further comprehend a heel lift construction in which the stop washers or flanges for the securing 85 nails are arranged parallel to the attaching 90 face of the lift, and will exert a uniform bearing pressure upon the material of the lift, so that upon the tendency of the lift to return to its normal condition, the resilient material will exert a uniform bearing pressure on the washers, and the washers will 95 not cut into or mutilate the material.

With the above and other objects in view, the invention consists in the improved resilient lift for shoe heels, and in the construction and arrangement of its several parts, as will be hereinafter more fully described, illustrated in the accompanying drawings, and subsequently incorporated in the subjoined claims.

In the drawings, wherein I have disclosed several practical embodiments of the invention, and in which similar reference characters designate corresponding parts throughout the several views:

Figure 1 is a perspective view showing one of the simpler forms of the improved heel lift construction.

Figure 2 is a longitudinal sectional view 5 showing the lift of Figure 1, with relation to the shoe heel before it is secured to the latter.

Figure 3 is a plan view of another form 10 of the heel lift, having a rand extending along its side and rear edges.

Figure 3^a is a plan view on a reduced scale, similar to Figure 3, graphically illustrating the lines of emergence of the angular surfaces at the breast corners of the lift.

15 Figure 4 is a longitudinal section of the lift shown in Figure 3 before it is secured to the shoe heel.

Figure 5 is a similar view of the lift after it has been secured to the heel.

20 Figure 6 is a plan view of another slightly modified construction.

Figure 7 is a longitudinal section thereof.

Figure 8 is a transverse section taken on the line 8—8 of Figure 6, and,

25 Figure 9 is a perspective view of the heel lift as shown in Figure 6.

In the drawings I have illustrated my improved heel lift for men's shoes, which is molded between suitable dies in the usual 30 manner from rubber or other composition material, having the requisite degree of resiliency as is now generally used in the art, in the production of such heel lifts.

The lift 5 is formed with a flat or plane 35 tread face 6. In this embodiment the attaching face of the lift also presents a continuous flat or plane surface 7.

In the molding of the lift, the breast portion 8 thereof is formed at an obtuse inclination 40 with respect to the plane of the body portion, such inclined breast portion extending across the entire width of the lift. In the embodiment shown, the upper or heel engaging surface 9 of the breast portion 8 of the lift gradually merges into the plane 45 surface 7, and there is no clearly defined line of demarkation between the surfaces 7 and 9. The lower or tread surface 10 of the breast portion 8 of the lift likewise gradually merges into the tread face 6 of the lift 50 body.

In the application of the lift, as above described, to the heel of the shoe, the lift is arranged as seen in Figure 2 of the drawings 55 with its surfaces 7 and 9 opposed to the face H of the shoe heel, and with the breast portion 8 of the lift engaged with the breast edge of the heel, while the rear rounded end of the lift is engaged with the rear edge of 60 the heel. Pressure is now applied to the bottom or tread face of the lift at the point of juncture of the breast portion 8 with the lift body, so that the lift is flattened out and the breast portion thereof disposed in 65 substantially the same plane as the body

portion. Thus a leverage action is applied, and the surfaces 7 and 9 of the attaching face of the lift are brought into intimate contact with the heel face.

In the molding of the lift, the body portion thereof, preferably inwardly of and in spaced relation to the marginal edges, is provided with a plurality of nail-receiving sockets 11, and at the inner ends of these 70 sockets the washers 12 are embedded in the structure of the lift. It is to be noted that these washers lie in a common horizontal plane, which plane is parallel with the tread and attaching faces of the lift. It is therefore apparent that when the resilient material of the lift is placed under tension, as a compressing pressure is applied thereto in attaching the lift to the shoe heel, such material, tending to return to its normal condition 80 will exert a uniform pressure on all portions of the washers. The securing nails, being driven at an angle of 90° to the plane of the heel, also exert a uniform pressure upon the washers, so that all tendency to move the washers angularly within the lift 85 structure with respect to their normal positions, will be obviated. Consequently, the possibility of the washers cutting into and mutilating the resilient material is overcome, and the life of the lift appreciably prolonged.

It will be readily seen that there is a constant tendency of the lift to return to its normal condition, and for the breast portion 8 thereof to again assume its obtusely inclined relation with respect to the body portion of the lift. This tendency acting against the resisting influence of the securing nails, causes the marginal edge portion and the breast edge and corners of the lift 100 to exert a tight hugging or compressing action against the margins of the heel face. The projecting edges of the lift may be freely trimmed off without destroying this tight frictional adhesion and positive compression 105 of the lift against the leather heel.

A heel lift as above described, and likewise of the forms which I will presently disclose, permits of a greater or more extensive range of trimming, so that the lift will accurately conform to the size and shape of the heel, and without, in any way, decreasing the tightness of the joint obtained around the marginal edges of the lift, than is possible in the familiar type of rand heel lift 110 now known in the art.

In the manner above explained I have succeeded in producing a heel lift which can be easily and quickly applied to the shoe heel without requiring the use of an adhesive, and which will stand very severe usage 115 without liability of the edge portions of the lift becoming separated or spaced from the heel face.

In Figures 3, 4 and 5 of the drawings, I 120

have disclosed another form of the invention, in which the lift is provided on its attaching face with a rand 14 extending along the side and rear edges thereof. This rand 5 presents a single inclined marginal surface on the attaching face of the lift, which merges into the horizontal plane surface 7'. The inclined rand surface extends to the breast edge 15 of the lift.

10 In this construction the breast portion 8' of the lift is also longitudinally inclined with respect to the lift body, as above described, the degree of inclination of the breast portion to the rear portion of the lift 15 being greater than that of the rand surfaces 14 to the plane surface 7', so that the inclined surface 9' of the breast portion at points adjacent to the breast edge of the lift is normally located above a plane coincident 20 with the side marginal edges of the rear portion of the lift. The molding dies for this form of the heel lift are preferably so constructed that the inclined or deflected breast portion of the lift will be produced 25 without resulting in sharply defined grooves or channels at the juncture of the inclined surface 9' of said breast portion with the end surfaces of the rand 14.

When pressure is applied to the tread face 30 of the lift, the marginal edge thereof is progressively brought into contact with the leather heel marginal surface from the rear end of the lift to the upwardly inclined breast portion 8', and with a gradually increasing frictional pressure, which pressure is uniformly distributed throughout the entire marginal edge portion of the lift. As the breast portion 8' straightens out into the plane of the body of the lift a leverage 35 action is exerted, tending to cause the resilient material to exert a maximum frictional pressure against the leather heel at the breast corners and along the entire breast edge of the lift. A similar though 40 somewhat less leverage action occurs as the surface of the rand 14 is forced into contact with the marginal side edges of the heel face, whereby a tight hugging pressure of the entire marginal edge of the lift upon 45 the heel is secured. This leverage action last referred to results from the fact that the deepest point of the rand 14 is at the juncture of the rand surface with the plane surface 7', and, as the nail is driven into the 50 shoe heel, this angular relationship gradually becomes less, until the lift is completely flattened, and thus caused to exert an intensive pressure against the face of the leather heel at its side marginal edges.

55 The essential feature of the construction last described resides in the offsetting of the breast portion of the lift at a longitudinal inclination without providing such breast portion with a rand, whereby a longitudinal resilient or spring action effect is secured,

and in the provision of the rand surfaces and the surface of said inclined breast portion, which results in producing a transverse resilient or spring action as the lift is flattened against the heel. In the merging of the surfaces 9' and 14 at the breast corners of the lift there is secured all the advantages of a heel lift having a continuous marginal rand without its objectionable feature, namely, the spacing of the breast corners from the heel face after the edges of the lift have been trimmed.

From reference to Figure 3, it will be noted that the nail-receiving sockets are so arranged that a radially distributed bearing pressure will be exerted upon the corner portions of the lift, and the substantially continuous surfaces 9' and 14 will contact throughout the surface area of the breast corners with the leather heel face. Thus the gaps or spaces between the breast corners of the lift and the leather heel, which must inevitably result in the use of a lift having a rand on the breast edge, as well as the side edges thereof, are entirely eliminated.

It is also to be noted that another important result incident to my improved heel lift construction is that the lift has a perfectly flat or plane tread face when attached to the shoe heel. The nail washers embodied in the resilient structure of the lift lie in a plane parallel to this tread face, and they will, therefore, sustain a uniform pressure upon the compression of the material of the lift, which bearing pressure on the nail washers is uniformly distributed throughout the marginal portions of the lift, and without cutting into or mutilating the material. The life of the heel lift is, therefore, greatly prolonged.

As illustrated in Figure 3 of the drawings, it will be appreciated from the above description that I have merely taken the ordinary rand type of heel lift, omitting the rand along the breast edge and then bent or deflected this breast portion of the lift upwardly at a longitudinal obtuse inclination from the lift body. In so doing, the rand portion on the marginal edge of the lift is likewise angularly bent in an upward direction along the dotted lines A, and said rand surface continues beyond this line upon the corner of the obtuse breast portion of the lift and merges with the inclined surface 9' along the dotted lines B. By this very simple improvement over the old prior art lift I have successfully demonstrated that the serious disadvantages present in the

latter, as heretofore explained, may be wholly obviated.

In Figures 6 to 9 inclusive of the drawings I have disclosed still another embodiment of the invention, in which preferably in the process of molding the lift there is

provided upon its attaching face, a centrally located raised portion or projection 17. The upper surface of this raised portion is normally below the plane of the 5 marginal edge of the lift, and its perimeter is chamfered, as at 18, and extends in parallel relation to said marginal edge. However, if desired, it is manifest that this projection 17 on the attaching face of the 10 lift may be of any other desired shape or form, or, as heretofore indicated, may be entirely dispensed with.

In the use of certain grades of rubber, with a heel lift constructed as seen in Figure 3, it is quite possible that with the attachment of the lift to the shoe heel the tread surface thereof will be depressed below a normal horizontal plane, so as to produce a cavity in the tread face of the 20 lift. Accordingly I propose to provide the attaching face of the lift with the projection 17, so that in attaching the lift to the heel this projection will engage the shoe heel when pressure is applied to the tread 25 face of the lift. This increased thickness of the central portion of the lift, and its compression, obviates the depression of the tread surface 6, as above referred to, when the lift is finally nailed to the shoe, and insures a perfectly flat or plane tread surface. 30

In the use of rubber lifts of the present new construction, it has been found that the tread of the wearer creating a compression of the rubber at the rear edge of the 35 lift causes a forwardly moving undulation on the tread face of the lift, as the rubber material absorbs, to a greater or less extent, the strains and stresses which are transmitted in a forward direction through 40 the lift body. This undulating action of the tread face of the lift results in the formation of a cavity or hollow in the tread surface just rearwardly of the breast edge, and therefore produces in effect, an uneven 45 tread. In my improved heel lift construction this objectionable feature is overcome, as the bend in the breast portion of the lift is located at the point where the hollow would otherwise be formed. When the lift 50 is flattened it is reinforced at this point by the compression of the material, and in intending to return to its initial passive condition, with the breast portion in angular relation to the lift body, compensates for 55 the forwardly moving undulation, so that the latter is obliterated as it approaches the breast edge of the lift. Thus the normal even wearing or tread surface is preserved, and without the buckling strain caused by 60 such undulating action during the use of the lift. This compression and reinforcement of the breast portion of the lift also obviates the possible opening or gapping

of the breast edge of the lift from contact with the heel face, or along the side marginal edges proximate to the breast corners of the lift. 65

From the foregoing description, considered in connection with the accompanying drawings, the construction, manner of use, and several advantages of my invention will be clearly understood. While for purposes of illustration I have described my invention in connection with a lift designed for application to men's shoes, it is apparent, of course, that the lift can also be molded in numerous other sizes for application to women's and children's shoes. 70 75

In the construction shown in Figures 3 and 6, it will be noted that the nail-receiving sockets are provided only in the inner body portion of the lift, in line with the surface 7, and that the fastening nails will not extend through either the breast portion 8' of the lift, or the marginal portion thereof, having the rand 14, since it is desired that these latter portions of the lift shall have a maximum of resiliency, so that they will possess the inherent function of maintaining a positive tight hugging pressure against the heel face. 80 85 90

In the present disclosure I have referred to several lift constructions which have given very satisfactory practical service, but it is to be understood that these lift constructions may be further modified in various respects, and I accordingly do not deem myself limited to the specific features of construction referred to, but reserve the privilege of adopting all such legitimate 95 100 105 alternative constructions as may be fairly embodied within the spirit and scope of the invention as claimed.

I claim:

1. A resilient heel lift having a major body portion and a minor breast portion, said last named portion inclined upwardly from a line extending transversely and entirely across the major portion and adjacent to the breast edge of the heel, the upper face of the breast portion forming a rand which extends from breast corner to breast corner. 105 110

2. A resilient heel lift having an attaching base provided with a rand portion extending entirely around the marginal portion of the lift, the rand portion near and at the breast corners of the heel being flat, the flat breast corner portions of the rand being inclined toward the adjacent flat breast and side portions of the rand. 115 120

In testimony that I claim the foregoing as my invention, I have signed my name hereunder.

WILLIAM J. TOMPKINS.
